BY Victor J. Evans

ATTORNEY

UNITED STATES PATENT OFFICE.

ELMER E. DAVIS, OF CISCO, TEXAS.

BIT.

Application filed October 6, 1922. Serial No. 592,837.

This invention relates to hydraulic fish-tail bits, and has for its object to provide the shank of the bit with spaced series of openings, with the series of openings lying at opposite sides of the blade of the bit and disposed at angles to allow water to pass over and wash the entire area of the blade, and in this way prevent mud or the like from clinging to the sides of the blade.

10 In carrying out the invention, I make the shank of the bit hollow to facilitate drilling of the holes or openings for the purpose above mentioned, without weakening the strength of the bit in its entirety.

15 Another very important object of the invention resides in providing the bit with reinforcing webs which extend downwardly from the shank and affords the plate the desired strength at a point immediately beneath the collar.

20 The nature and advantages of the invention will be better understood when the following detailed description is read in connection with the accompanying drawing, the 25 invention residing in the construction, combination, and arrangement of parts as claimed.

25 In the drawing forming part of this application, like numerals of reference indicate similar parts in the several views, and wherein:

30 Figure 1 is a side elevation of the bit.

Figure 2 is an edge elevation.

35 Figure 3 is a sectional view taken on line 3—3 of Figure 1.

Referring to the drawing in detail, 10 indicates the blade of the bit which is of well-known construction, while the shank which associates the bit with the drill collar (not 40 shown) is indicated at 11. This shank is hollowed to facilitate drilling of the holes or openings indicated at 12, and which holes are arranged in a series, the latter lying at opposite sides of the blade 10. The shank 45 is hollowed in a manner to provide for the proper thickness of the material at the bottom of the shank through which the holes 12 are drilled so as not to materially weaken the bit in its entirety. It will be noted that 50 the holes or openings 12 are disposed at such angles that water passing through these

holes will wash the entire area of both sides of the blade and in this way prevent mud or the like from clinging to the blade, which at present is a source of trouble with bits 55 of this character.

It will be noted from an inspection of the drawing that the shank is extended to provide reinforcing webs or ribs 13, which are arranged at opposite sides of the blade 60 10 immediately beneath the shank, and affords the blade, the desired strength at that point where it is most needed, namely, beneath the collar 11.

While it is believed that from the foregoing description, the nature and advantages of the invention will be readily apparent, I desire to have it understood that I do not limit myself to what is herein shown and described, and that such changes may be 70 resorted to when desired as fall within the scope of what is claimed.

What I claim is:

1. A fish tail bit comprising a blade, a hollow shank arising therefrom and including an annular thickened portion at its point of junction with the blade and ribs connecting each face of the blade adjacent each side edge of the faces of the blade with the enlargement extending downwardly upon the 80 blade for a distance approximately equally one-third of the length of the blade.

2. A fish tail bit comprising a blade, a hollow shank arising therefrom and including an annular thickened portion at its 85 point of junction with the blade and ribs connecting each face of the blade adjacent each side edge of the faces of the blades with the enlargement extending downwardly upon the blade for a distance approximately 90 equally one-third of the length of the blade, said thickened portion being provided with series of spaced bores formed in the enlargement and arranged at opposite sides of the blade with the bores of each series opening 95 into said socket at the upper ends thereof and through the bottom of the enlargement intermediate said ribs and at the junction of the enlargement with the blade through the lower ends thereof.

100 In testimony whereof I affix my signature.

ELMER E. DAVIS.
